UNITED STATES PATENT OFFICE.

OMAR E. CLARK, OF DENVER, COLORADO, ASSIGNOR TO THE DENVER ROCK DRILL MANUFACTURING COMPANY, OF DENVER, COLORADO, A CORPORATION OF DELAWARE.

ENGINE.

Application filed June 19, 1919. Serial No. 305,249.

To all whom it may concern:

Be it known that I, OMAR E. CLARK, a citizen of the United States, residing at Denver, in the county of Denver and State of Colorado, have invented certain new and useful Improvements in Engines, of which the following is a specification.

The present invention relates to motor structures, and one of the primary objects 10 is to provide a very compact mechanism of relatively simple structure that will operate at high speed and produce a relatively great amount of power.

A further and important object is to provide such a motor coupled up to or built in 15 a driven mechanism, so that the entire apparatus will occupy but a small amount of space, and is thus peculiarly applicable for use in confined places.

20 In the accompanying drawings:—

Figure 1 is an end elevation of the preferred embodiment of the invention.

Figure 2 is a similar view with the head plate removed.

25 Figure 3 is a cross sectional view on the line 3—3 of Figure 4.

Figure 4 is a longitudinal sectional view.

Figure 5 is a detail face view of a portion 30 of the casing head plate with the controlling valve removed.

Figure 6 is a detail perspective view of the spindle member.

Figure 7 is a detail sectional view through one of the relief valves.

35 Figures 8 and 9 are detail sectional views through the controlling valve structure, showing a valve in different positions.

Similar reference numerals designate corresponding parts in all the figures of the 40 drawings.

In the embodiment illustrated, a support is employed, comprising a base 12 which may be of any suitable configuration, but preferably has a recessed portion 13 forming 45 part of a clamp member, so that the apparatus can be mounted on a rock drill supporting column or the like. One end of this support is provided with a casing 14 having a removable head plate 15, and said 50 head plate carries an integral spindle 16 that is disposed eccentrically to the peripheral wall 17 of the casing. The opposite wall of

said casing is provided with a concentrically disposed journal bearing 18 preferably of the roller or ball type.

Within the casing 14 is located a rotatable drum member 19 having a gudgeon 20 journaled in the bearing 18. Said drum member thus rotates on an axis that is eccentric to the spindle 16. The said drum 60 member, as shown in Fig. 3 is angular in section, being provided with four flat walls 21, to the inner sides of which are secured wear plates 22.

A cylinder block 23 is rotatably mounted 65 on the spindle 16, and is also provided with radial cylinders 24, in which reciprocate hollow pistons 25 that project beyond the outer ends of said cylinders. These pistons 25 are provided at their outer terminals 70 with oppositely extending ears 26, in which are journaled rollers 27 that run upon the wear plates 22.

Motive fluid from any suitable source is supplied to the motor above described 75 through a valve casing 28 mounted on the head plate 15. Said valve casing has an intake nipple 29 to which a supply hose or other conduit is connected. This nipple opens into a central chamber 30 in the valve 80 casing 28, and on opposite sides of said central chamber are other chambers 31 and 32 in communication with the central chamber by means of ports 33 in the partitions that define said chambers. The chambers 31 and 85 32 communicate with passageways 34, 35, extending longitudinally through the spindle 16, said passageways being also in communication with opposite ports 36 and 37 laterally opening through the periphery of said spindle. The cylinder block 23 is provided with ports 38 opening into the different cylinders and arranged to alternately communicate with the ports 36 and 37 as the cylinder block 90 rotates. The valve casing 28 is furthermore provided with exhaust ports 39 located outside the chambers 31 and 32 and in communication with the same through ports 40.

It will be noted that the ports 37 and 40 are in alignment and receive a reciprocating 100 controlling valve 41 having a central groove 42 and cut away ends or channels 43 and 44, one end of the valve 41 having an extended shank in the form of a rack 45 engaged by a

gear segment 46 journaled in one end of the valve casing 28 and having an exposed actuating handle 47.

The passageways 34 and 35, as already explained, extend entirely through the spindle 23 and their inner ends are provided with relief valves as indicated in Figure 6, one of said relief valves being shown in detail in Figure 7. Each of the valve structures, as illustrated, comprises a hollow plug 48 that is threaded into the passageway, and has in turn threaded into it another plug 49 having a central bore 50 that terminates in a valve seat 51. A ball valve 52 cooperates with the seat and is normally held thereagainst by a spring pressed plunger 53 slidably mounted in the inner end of the plug 48. The bore of said plug 48 is in communication with the passageways in which the plug is placed, by means of ports 54 communicating with said bore and with the passageway.

Briefly outlined, the operation of the apparatus is as follows: When the controlling valve is in its central position, as shown in Figure 1, motive fluid supplied to the central chamber with the nipple 29 is denied access to the motor. When the valve is shifted to the position shown in Figure 10 motive fluid will flow from the chamber 30 to the chamber 31, and thus pass through the passages 34 and through the port 36. As a consequence it will enter each cylinder as indicated in Figure 3, as rapidly as the ports 38 communicate with the ports 36. The eccentric mounting of the cylinders with respect to the drum will thus cause the said drum to rotate in the direction indicated by the arrows in Figure 3. During their inward movement the cylinder ports 38 are in communication with the port 37 as illustrated in Figure 3, and consequently the exhaust passes into the channels 35, thence into the chambers 32 and out through the exhaust port 39. If the valve is shifted to the opposite extreme, as illustrated in Figure 8, the flow of fluid is just the reverse or as illustrated in Figure 3, and consequently a reverse rotation of the drum takes place. The outer casing may be utilized as a lubricant container and as the drum rotates therein, it will be evident that the lubricant will be carried and splashed over the mechanism, thus insuring thorough lubrication. It furthermore occurs that there is ordinarily some leakage past the pistons which may build up pressure in the drum, but this pressure is taken care of by the relief valves 48-53, one set of which is of course always connected with the exhaust permitting means, and thus allows any excessive pressure to open the valve 52 and enter such means. On the other hand, the pressure against those valves which are in the supply passages, serves to maintain the said valves closed.

While it will be evident that the motor

above described may be utilized for various purposes, it is especially applicable for operating a hoisting drum of the type used in confined places, such as mine work. It therefore is illustrated as part of an apparatus of that character. To the gudgeon 20 is fixed a tapered shaft 55 rotatably mounted in a fixed housing 56 secured to the wall of the casing 14 in which said gudgeon 20 is journaled. Rotatably mounted on the housing 56 is a winding drum 57 having at one end a brake flange 58. Its opposite cable retaining wall or flange has an internal gear 59. The outer end of the housing 56 is engaged with a gear case 60 that encloses the internal gear 59 and has its inner open side closed by the drum flange that carries the internal gear 59. Said gear case also contains a gear 61 mounted on a shaft 62, said shaft having a pinion 63 in mesh with the internal gear 59. A pinion 64 is in mesh with a gear wheel 61 and is carried by a sleeve 65 feathered as illustrated at 66 on the end of the shaft 55, the sleeve projecting from the gear case 60 and having a suitable actuating knob 67. A brake band 68 of any desired type and operated by any suitable means, not shown, cooperates with the brake flange 58 in a manner well understood.

It will be evident that when the apparatus is suitably clamped to a support or holding means, if the engine is run in either of opposite directions, the shaft 55 will be correspondingly driven, and if the pinion is positioned so that it is in mesh with the gear 61, the drum 57 will be rotatated. If desired the pinion 64 can be moved to a position where it is out of mesh with the gear 61, so that the winding drum will be free to rotate in either direction independently of the motor, its movement being controlled by the brake band 68.

From the foregoing, it is thought that the construction, operation and many advantages of the herein described invention will be apparent to those skilled in the art, without further description, and it will be understood that various changes in the size, shape, proportion, and minor details of construction, may be resorted to without departing from the spirit or sacrificing any of the advantages of the invention.

Having thus fully described my invention, what I claim as new, and desire to secure by Letters Patent, is:

1. In apparatus of the character set forth, the combination with a support including spaced casing elements, one of which has an open inner side, of a winding drum journaled between the casings and including a cable retaining side wall that constitutes a closure for said open inner side, a motor in the other casing, a shaft driven by the motor and extending through the drum, and gearing in the open sided casing driven

by the shaft and engaged with the said side wall of the drum.

2. In apparatus of the character set forth, the combination with a support, of a motor mounted on one end of the support, a gear case mounted on the other end of the support and having an open inner side, gearing in the gear case, means operated by the motor for driving the gearing, and a winding 10 drum mounted between the motor and the gear case and including a cable retaining flange that closes the open inner side of the gear case and is provided with a gear with which the gearing in the gear case engages.
- 15 3. In apparatus of the character set forth, the combination with a support including spaced casing elements, one of said casing elements having an eccentric spindle there-

in, and a concentric bearing, of a drum journaled in the bearing and surrounding 20 the spindle, a cylinder block rotatable on the spindle, pistons in the cylinders of said block operating against the drum, means for supplying motive fluid through the spindle to the cylinders, a shaft extending from 25 the drum to the opposite casing, a drum rotatable around the shaft, and gearing in the second casing connecting the shaft and drum.

In testimony whereof, I affix my signature 30 in the presence of two witnesses.

OMAR E. CLARK.
